(57) **CLAIM**

The ornamental design for an egg carton as shown and described.

DESCRIPTION

FIG. 1 is a top perspective view of an egg carton showing the new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof;

FIG. 7 is a left side elevation view thereof; and,

FIG. 8 is a front perspective view thereof illustrating the egg carton in an open configuration.

The dash-dash type broken lines shown in the drawing views are included for the purpose of showing environmental subject matter that forms no part of the claimed design.

1 Claim, 7 Drawing Sheets(56)
